(57) **CLAIM**

The ornamental design for a wreath, as shown and described.

DESCRIPTION

FIG. 1 is a front elevational view of a first embodiment of a wreath showing my new design;

FIG. 2 is a rear elevational view thereof;

FIG. 3 is a top plan view thereof; and

FIG. 4 is a bottom plan view thereof.

FIG. 5 is a right side elevational view thereof, a left side elevational view thereof being a mirror image; and

FIG. 6 is an enlarged bottom plan view thereof.

FIG. 7 is a front elevational view of a second embodiment of a wreath showing my new design;

FIG. 8 is a rear elevational view thereof;

FIG. 9 is a top plan view thereof;

FIG. 10 is a bottom plan view thereof;

FIG. 11 is a right side elevational view thereof;

FIG. 12 is a left side elevational view thereof; and

FIG. 13 is a front perspective view thereof.

The oblong shapes at the ends of the tabs in FIGS. 1 and 2 shown inside the ring represent cuts in the surface of the design. The leaf outline shown in broken lines that is unclaimed in FIGS. 1, 2, 7-13 shows an opening in which the solid lines of the folded side of the wreath are visible.
